[57] ABSTRACT

Explosive force is generated in a fluid such as water enclosed in a strong steel cylinder by suddenly raising some of the fluid between concentrically placed and closely spaced electrode elements to the plasma state by means of a high voltage condenser bank with its power supply and a highly insulated electric switch in series electric circuitry with the condenser bank and the electrode elements. Means are employed to close switch contacts automatically when the power supply in parallel electric circuitry with the condenser bank has charged the condenser bank to an adjustable voltage value consistent with the explosive force required for a particular pumping need.

One way check valves allow the explosive force to cause the ramming action on the fluid in one direction and entrance of new fluid into the cylinder to take place from another port from which exit is prevented thereby providing a one direction ramming action.

SHOCK PLASMA HYDROSTATIC RAM

This invention is a type of hydraulic ram somewhat similar to the hydraulic rams which derive energy to pump water from the momentum of streaming water whereby when the streaming water is suddenly stopped by a valve closing at the downstream end of the column of water the pressure surge that follows is used to open another valve and force the water into another channel where the same pressure is able to carry the water to a higher elevation. This invention then is similar in that a downstream valve is closed and in that fluid is rammed by means of a pressure surge through a valve which admits water or fluid into an adjacent channel where the same pressure carries it to a high elevation and after the surge this check valve closes to prevent the fluid from returning down the channel. However, the inventive concept here consists in deriving the energy for the ramming effect not from the momentum of streaming water or fluid but from an explosive plasma caused by the discharge of a high-voltage, high-amperage condenser bank across a two element electrode immersed in water in a pressure chamber. This pressure chamber may be separated by a free floating piston from the fluid to be rammed or it may simply consist of the electric discharge in the water itself that is being rammed provided the housing and the valves which contain the water are of sufficient strength to sustain a pressure surge of the magnitude produced by a shock plasma. The mechanism of the electrode which produces the pressure surge from the shock plasma is briefly described. When electric current from the condenser bank is caused to pass from one element of the electrode to the other through water the water is instantly ionized and converted to a highly conductive plasma which reacts as a resistance would for the production of heat under the influence of a great surge of voltage and amperage. Electric energy is thereby converted to heat energy in a manner rapid enough to produce a strong explosive effect. It is the pressure surge from this explosive effect which is desired and which does the work in this invention which in ordinary hydraulic rams is done by the pressure surge caused by suddenly stopping a streaming column of water or fluid.

The drawings which follow will help to clarify the inventive concept and to explain it in greater detail.

A brief description of each figure follows.

FIG. 1 is a physically strong two element electrode.

FIG. 2 is a transverse view of this electrode showing the concentric placement of the electrode elements and their separation by high-voltage insulation.

FIG. 3 is the steel cylinder ram housing with plugs at both ends into which are inserted check valves and electrode.

FIG. 4 is a high-voltage electric switch.

FIG. 5 is a schematic drawing of automatic switch closing mechanism.

FIG. 6 is adaptation of basic ram as shown in FIG. 3 to pump fluids other than the fluid being used to produce the plasma.

FIG. 1 depicts the two element electrode which is used to produce the percussion or pressure surge in the water by means of electric discharge across its elements through the water. Of this FIG. 1 is the outer conductive element of the two element electrode. It has the physical strength to support inner element and insula-

tion under impact of explosive effect. It is electrically connected to sleeve 2 which carries grounded potential from the condenser bank. Number 3 is the second electrode element at the center of the electrode and is electrically connected to cable 6 by connecting sleeve 5. Number 4 is a polyester plastic embedded with fiberglass or a very strong ceramic. Its purpose is to electrically insulate electrode 3 from electrode 1 and to rigidly support electrode 3 which it does by means of its strength and by threading. It is able to sustain shock as well as high voltage. Number 7 is high-voltage insulating sleeve embedded in plastic insulation 4 and encircling cable 6 the entire length of the cable to the high voltage switch which engages the condenser bank.

FIG. 2 is a transverse sectional view showing relative positions of 1, 2, 3 and 4 which numbers are the same representations as in FIG. 1. This view is for the purpose of explaining that the radial separation in distance of 1 from 3 is important with respect to the voltage and capacitance in the condenser bank. When a voltage of 6,000 volts was used with a condenser bank of 400 microfarads a strong pressure surge was produced in water when the separation radially between the outer surface of electrode 3 and the inner surface of electrode 1 was three-quarters of an inch and the diameter of inner electrode 3 was one-fourth of an inch. Less voltage and capacitance is required for lesser power requirements.

FIG. 3 illustrates the basic ram elements less condenser bank, power supply, switching and automatic controls. In FIG. 3 number 10 is the electrode described in FIGS. 1 and 2 shown now in its position in the ram. Number 12 of this figure is a strong steel housing in the form of a cylinder threaded on the inside. Check valves 13 and 14 are of the heavy duty variety and are for the purposes respectively of emitting only and admitting only water into compression cavity 16. Threaded disc 15 receives by means of threaded holes check valve 13 and electrode 10. Threaded disc 17 similarly by means of threads is screwed into cylinder 2 and in turn receives check valve 14 by means of threading.

FIG. 4 illustrates a high-voltage, high-amperage switch which can be remotely or automatically controlled by the current admitted to a solenoid which controls it. Contact points 21 of this switch are constructed of heavy pieces of copper or tungsten. Number 24 is a stationary support for a contact point constructed of a strong tube of electrically insulating plastic. Moveable lever arm or armature is constructed of the same material as 24 and this 25 is connected on its lower end to hinge 28 by means of which it can rock back and forth with a long swing of several inches to move contact points in and out of contact with each other. Insulating terminal 22 with connector enables flexible cable 26 to be connected to contact point 21 and it facilitates connection of same cable 26 to remainder of circuitry. Solenoid 23 with moveable arm extending on the left and connecting terminals at its base has magnetic windings which when energized pull lever arm and lever to the right. The function of pungee cord 27 which consists of a heavy band of rubber is to absorb shock from the fast acting solenoid and its lever arm and prevent sudden strain on lever arm 25. The purpose of spring 29 is to close the contact points and

to keep them closed when the current is off thus preventing the accumulation of an inadvertent charge on the condenser bank.

FIG. 5 is a schematic diagram of basic components and automatic discharge mechanism. Electrode 10 is described in more detail in previous figures. Switch 32 is the one described in FIG. 4. Condenser 33 represents the high-voltage large capacitance which when discharged by means of the switch 32 through water across elements of electrode 10 produces the surge in pressure. Rectifier 34 in conjunction with high voltage from transformer 35 charge condenser bank 33. When voltage over 6,000 volts is used and a condenser capacitance value of 400 microfarads is charged a very powerful pressure surge is obtained. The time required for the charging process is dependent upon the resistance of the high-voltage winding. If charging and discharging are too rapid and heat build up exceeds heat capabilities of transformer rectifier or condenser bank etc. a resistance may be added in series between the transformer and rectifier. The following elements contribute to an automatic operation of the device. Voltage divider 36 across the condenser bank is of the variable variety and has the function of sampling a calibrated fraction of the total voltage desired across the condenser bank and to use this as an index voltage for energizing relay 38 through ionizing tube 37 which gives positive on-off action to relay 38. When relay 38 is energized contacts open de-energizing electric switch 32 which causes it to engage its contact points thereby discharging condenser 33 through electrode 10. By setting sliding contact of voltage divider 36 closer to the condenser banks lower plate as drawn in the diagram more voltage must charge across the condenser bank before there will be sufficient voltage to ionize the gas in the ionization tube 37 and energize relay 38 causing its points to open and the points of 32 to close. When condenser bank has sufficiently high voltage capabilities 10,000 volts with 800 microfarads can be used for extreme pressure surges for very deep wells or high pressure pumping and 6,000 volts with 100 microfarads or even less can be used for lower pressure requirements with variations in between. The only real limits to be set are those depending upon pressure and shock sustaining capabilities of ram housing and piping as well as electrode separation, higher voltages requiring greater separation of electrode elements.

FIG. 6 is very similar to FIG. 3 with the exception that there is an addition of a free floating piston spring-loaded to hold it at the upward end of its stroke. The fluid such as water in cavity 48 is separated from another fluid such as oil in cavity 46 by means of free floating piston 49 which is mounted in cylinder 40 which is open on its lower end and filled in its portion beneath the piston with the fluid from cavity 46 into which cavity this part of cylinder 40 extends. The pressure and explosive shock which takes place in cavity 48 is transmitted to the fluid in cavity 46 where check valves 43 and 44 convert this alternating pressure into a fluid flow upward and out from check valve 43 and inward through check valve 44. Again as in FIG. 3 discs 47 and 5 are threaded to cylinder 42 to form the main pressure vessel. Threaded holes through discs 45 and 47 admit and support electrode 1 and check valves 43 and 44. Pipe 41 maintains water in plasma forming

chamber 48. An alternating pressure-vacuum on this line exhausts unwanted residual gases from the plasma and maintains the water level immersing the electrode elements.

I claim:

1. A pump comprising:
  - a. a strong cylindrical chamber capable of sustaining explosive shock impact from an electric shock plasma of at least 2,000 volts from a condenser bank of at least 200 microfarads, said cylinder being threaded on its inner surface to permit securing of thick metallic plugs or plates in both ends and
  - b. a strong ball-type check valve threaded on its outer cylindrical surface and fitted by means of same threads to a flow tube to be described, the steel ball of said valve being seated in a conical receptacle which has a hole at narrow lower end of this cone able to transport fluid from shock chamber to the valve and flow tube said check valve being opened by explosive shock and held open by upward momentum of fluid rush and closing when upward flow has ceased, the closing being accomplished by its own weight, by returning weight of water column above it and by spring action, said ball valve being so seated in conical opening as to allow exit only of fluid from within the chamber and
  - c. another strong ball-type check valve in the lower area of the shock chamber threaded on its outer cylindrical surface and fitted by means of threads into lower plug to be described said check valve normally in closed position by spring action or by pressure of fluid in the chamber or by its own weight and by explosive action of shock plasma but of such tension that it is opened by vacuum produced by rising column of fluid above it, the ball valve of said check valve being so seated in conical seat as to allow admission only of fluid into chamber and
  - d. a threaded plug secured by means of threading into upper end of shock chamber cylinder said plug or plate having two threaded holes, one larger hole being adapted to the threads of the upper check valve and the threads of the smaller threaded hole being adapted to and supporting the outer cylinder of the two element electrode and
  - e. a second threaded plug secured by means of threading into the lower end of the shock chamber cylinder which plug contains a hole threaded to support the lower check valve and
  - f. a two element electrode of which the inner electrode is a strong threaded metal rod which is enclosed in a plastic or ceramic insulating cylinder and secured to it by means of threading extending circumferentially the entire length of said bar and by threading on the inner wall of said insulating material cylinder which is physically strong, of high voltage insulating quality and of a thickness of an eighth of an inch or more consistent with element separation for strength of plasma desired, this same cylinder in turn being enclosed in a metallic cylinder and secured to it by means of threading preventing relative movement between the two cylinders with outer threads on electrodes

outer tube being adapted for support in the upper plug's threaded smaller hole and allowing the electrode to be inserted deep within the shock chamber and

g. a flow tube connected by means of threading to the upper threaded end of the upper check valve such tube or pipe being of such length and size as to allow a surge of fluid and permit a column of such fluid to acquire a momentum as it exits from that check valve and

h. a high-voltage heavily insulated cable adapted with a threaded connector whereby it is able to carry current from the condenser bank to the inner rod element of the electrode through a high-voltage switch and

i. a cable connector to the metal pipe or flow tube whereby the cable carrying the opposite polarity current from the condenser bank is connected to the metallic surfaces for conduction of current through the pipe, the chamber and the plug to the outer element of the electrode.

2. A pumping device in accord with claim 1 wherein the high-voltage switch in series connection between the condenser bank and the center rod-element of the electrode comprises:

a. a heavy duty hammer-like contact point fastened at the top of a strong electrically insulating support cylinder said contact point being adapted by threading to receive a high-voltage high-amperage cable connector said support cylinder being securely fastened at its base to cause it to be rigid and

b. another heavy duty hammer-like contact point fastened at the top of a strong electrically insulating supporting cylinder said contact point being adapted by threading to receive a high-voltage high-amperage cable connector, the above mentioned supporting cylinder being fastened on the bottom end to a hinge allowing a pivoting swing in one plane wherein at one end of the swing the hammer-like contact point contacts the other rigid contact point and at the other end of its swing is at least several inches removed from the rigid contact point and

c. a short length of flexible multistranded high-voltage cable of a few feet or more in length which is connected by a cable connector at one end to the pivoting contact point and so formed into an arc between that point and the other rigidly held terminal connector that when the pivoting contact swings to and fro in its switching swing the cable may move freely by changing the degree of its arc and

d. a heavy duty electric solenoid with its electro-magnetically activated sliding arm the motion of which arm in and out is in the same plane as is the swing of the pivoting contact point in its support cylinder and

e. a rubber or plastic pungee cord which transmits the sliding action of the solenoid arm to the pivoting contact point near the lower portion of the contact point supporting cylinder this being accomplished by the elasticity of the pungee cord in such a way as to absorb some of the shock from the solenoid when it is electrically excited and

f. a spring attached to the pivoting contact support cylinder which acts to keep contact points normally closed and

g. an electric switch which completes or interrupts the current to the solenoid whereby wide opening of the contact points in series between the condenser bank and the outer element of the electrode is effected for a period of charging the condenser bank said electric switch opening to release tension on solenoid thereby allowing heavy duty high-voltage contacts to be engaged and current to flow through the electrode.

3. A pumping device as in claim 2 in which the solenoid engaging-disengaging switch comprises:

a. a resistance type voltage divider placed across the main condenser bank which voltage divider has a sliding center contact bar and two end terminals and

b. an ionizing tube which ionizes when a fraction of total condenser bank voltage reaches a value determined by position of sliding contact bar and ionization potential of the gas in the tube such potential thereby being an index of the total potential across the bank and

c. a relay in whose coil is series circuit connection between contact bar of voltage divider ionization tube and an end terminal of same voltage divider and whose points are so connected that contact is made when the relay coil is not activated and these same points are used to switch on and off the relay.

4. A pumping device comprising:

a. a strong cylindrical chamber capable of sustaining explosive shock impact from an electric shock plasma of at least 2,000 volts from a condenser bank of at least 200 microfarads, said cylinder being threaded on its inner surface to permit securing of metallic discs or plugs in both ends and

b. inside of same cylinder another smaller cylinder open on both ends and of very strong metallic composition allowing it to sustain explosive shock impact from an electric shock plasma of at least 2,000 volts from a condenser bank of at least 200 microfarads said smaller cylinder being threaded for a short distance on the inside of its upper end adapting it to the threading of an electrode to be described, said smaller cylinder having a metallic spider web secured on the inside of its lower end to support a spring coiling upward within and

c. within this smaller cylinder a free moving piston held in the center of said cylinder by the action of a spring supported on its lower end by aforementioned spider web,

d. a strong ball-type check valve threaded on its outer cylindrical surface and fitted by means of same threading into a plug or disc to be described and on its outer end fitted by means of threads to a flow tube to be described, the steel ball of said valve being seated in a conical receptacle which has a hole at its narrow lower end which is able to transport fluid from the shock chamber through the valve to the flow tube said check valve being opened by explosive shock from the chamber and held open by upward momentum of fluid rush and closing when upward rush has ceased, the closing being accomplished by its own weight, by return-

ing weight of the water column above it and by spring action, said ball valve being so seated in conical opening as to allow exit only of fluid from within the chamber and

- e. another strong ball type check valve in the lower area of the shock chamber threaded on its outer cylindrical surface and connected by means of these same threads into the lower plug to be described, said check valve normally in closed position by spring action or by its own weight and by explosive action of shock plasma but of such tension that it is opened by vacuum produced by rising column of fluid above it, the ball valve of said check valve being so seated as to allow admission only of fluid into the chamber and 5
- f. a threaded plug or disc secured by means of threading into the upper end of shock chamber cylinder said plug or disc having two threaded holes, one larger hole being adapted to the threads of the upper check valve and the threads of the 10 smaller threaded hole being adapted to and supporting the outer cylinder of the two element electrode and
- g. a second threaded plug or disc secured by means of threading into the lower end of the shock 25 chamber cylinder which plug contains a hole threaded to support the lower check valve and
- h. a two element electrode of which the inner electrode is a strong threaded metal rod which is securely fastened to and enclosed in a plastic or 30 ceramic cylinder of high voltage insulating qualities by means of same threading which extend the entire length of the bar and the cylinder, which cylinder being physically strong is itself enclosed in

15

35

and secured to a metallic cylinder by same threading on outer side of plastic cylinder and inner surface of metallic cylinder there being threading also along entire outer surface of this outer metallic cylinder adapting it for support in the upper plugs threaded smaller hole and allowing the electrode to be inserted deep within the shock chamber where this same threading adapts it to the smaller inner cylinder with the free moving piston and

- i. a flow tube connected by means of threading to the upper threaded end of the upper check valve such tube or pipe being of such length and size as to allow a surge of fluid and permit a column of such fluid to acquire a momentum as it exits from that check valve and
- j. a high-voltage heavily insulated cable adapted with a threaded connector whereby it is able to carry current from a condenser bank to the inner rod element of the electrode through a high-voltage switch and
- k. a cable connector to the metal pipe or flow tube whereby the cable carrying the opposite polarity current from the condenser bank is connected to the metallic surfaces for conduction of current through the pipe, the chamber and the plug to the outer element of the electrode and
- l. a water inlet-outlet tube extending through the outer chamber wall into the inner smaller chamber whereby water from an auxiliary system is forced into the small shock chamber for plasma generation and whereby exhaust material and gases are removed to prepare inner chamber for subsequent discharges.
